UNITED STATES PATENT OFFICE.

WILLIAM A. MOREY, OF LONGBEACH, CALIFORNIA.

AMUSEMENT DEVICE.

1,089,004.

Specification of Letters Patent.

Patented Mar. 3, 1914.

Application filed August 27, 1913. Serial No. 786,826.

To all whom it may concern:

Be it known that I, WILLIAM A. MOREY, a citizen of the United States, residing at the city of Longbeach, in the county of Los Angeles and State of California, have invented new and useful Improvements in Amusement Devices, of which the following is a specification.

My invention relates to a device for illustrating a collision between a steamship and an iceberg and the resultant sinking of the steamship, and the object thereof is to produce a simple and efficient device for that purpose for use upon the stage of a theater 10 or like place. I accomplish this object by the device described herein and illustrated in the accompanying drawings forming a part hereof, in which:

Figure 1 is a diagrammatic view of my 20 device showing the various positions of the ship during the scene. Fig. 2 is a front elevation of the steamship and its adjunct parts partly broken away. Fig. 3 is a top plan of Fig. 2. Fig. 4 is a section on the 25 line 4—4 of Fig. 2. Fig. 5 is a front elevation of the iceberg. Fig. 6 is a section on the line 6—6 of Fig. 5.

In the drawings 10 represents a shield or plate preferably of sheet metal and painted 30 or otherwise decorated to represent a side elevation of an ocean going steamship, and is pivotally mounted centrally thereof at near the top to the upper end of a T shaped guide beam 11 by pivot 12. Beam 11 extends downwardly and the lower end is slidably received in and guided by a T slot 13 cut in the side of a guide block 14 secured to a standard 15. Standard 15 extends downwardly and is secured at its lower end to a 40 cross beam 16 by bolts or otherwise and braces 17 and 18. Cross beam 16 is provided at each end with axles 19 upon which are mounted wheels 20 for a purpose hereafter described.

Guide beam 11 has a slot or groove 21 longitudinally cut in the outer side thereof intermediate its ends and registers with a similar slot or groove 22 cut in the inner side of the guide block 14. A toothed rack 50 or plate 23 is rigidly secured to guide beam 11 in slot 21, the teeth of which extend into slot 22 in block 15 and slide therein. A gear or pinion 24 is mounted in bearings 25 upon the outer side of standard 15 near the 55 top thereof and extends through a slot 26 in said standard 15 and meshes with rack 23.

A smaller pinion 27 is mounted on shaft 28 mounted in bearings 29 upon the outer side of standard 15 and meshes with gear 24.

A crank or handle 30 is secured upon one 60 end of shaft 28 and provides means to rotate said gear and pinion when desired. Shield or plate 10 has the lower corner representing the prow of the boat cut to represent the said corner as being broken off and 65 a plate 31 is pivoted at the lower end of a swinging lever 32 to normally hide said break. Lever 32 is pivoted at its upper end to the back of shield 10.

The iceberg 33 consists preferably of a 70 main or body member 33 which is supported at the desired distance from the floor in any suitable manner. This body member has an L shaped guide slot 34 cut at about the center thereof and having the longer leg there- 75 of extending downwardly in which is received a square guide pin or block 35 secured to the back or inner side of the movable member 36.

In the operation of a scene embodying my 80 device a curtain or drop (not shown) painted to represent the sea will first be drawn across the stage. This curtain will extend upwardly from the floor of the stage to the waterline of the steamship. The iceberg 85 will be mounted at one side of the stage, partly behind the drop so as to represent an iceberg rising out of the water, with the parts as shown in Fig. 5. The steamship will be at the side of the stage opposite the 90 iceberg and behind the drop and will be wheeled across the stage toward the iceberg until the plate 31 strikes against the iceberg. This will cause said plate to be forced back and disclose the break in the hull of the 95 steamship. At the same time the attendant or operator will slide back the movable member 36 until block 35 is above the longer leg of the guide slot which will allow said supplementary member to drop and disappear 100 behind the curtain and representing a piece of the iceberg as being broken off by the force of the collision. After plate 31 has been forced back to disclose the break in the hull of the vessel the attendant or operator 105 will rock shield 10 on its pivot so as to cause the front end to rise upwardly and at the same time will wheel the steamship toward the berg so as to represent the said ship as sliding up on the iceberg a short distance. He will then draw the steamship 110 away from the berg a short distance when the

said ship will be brought to an even keel by gravity. He will then rock the said shield so as to tip the front end downwardly and at the same time will turn crank 30 and 5 gears 24 and 27 and gradually lower the shield 10 until it disappears behind the curtain, thus representing the sinking of the vessel.

Having described my invention, what I 10 claim is:—

1. An amusement device comprising the representation of an iceberg composed of a body member and a movable member attached thereto, said body member having 15 an L shaped slot therein and said movable member having a pin entering said slot; in combination with the representation of a ship composed of a shield or plate having one of the lower corners of irregular form to 20 represent a break and a movable plate adapted to lie against said corner and prevent said irregular corner being observed.

2. In an amusement device the representa-

tion of a steamship comprising a shield or plate cut to substantially the outline of a 25 steamship, and having the lower corner of the prow formed to represent a break therein; a movable plate pivotally mounted upon the back of said shield, normally hiding said break and being adapted to be moved to disclose said break; a support for said shield pivotally connected thereto centrally at near the top; and means to raise and lower said shield when desired.

3. In an amusement device the representation of an iceberg comprising a body member and a movable member; a slidable connection between said members; and means to support said members.

In witness that I claim the foregoing I 40 have hereunto subscribed my name this 20th day of August, 1913.

WILLIAM A. MOREY.
